PNEUMATIC CRUTCH PAD

Clarence M. Fallon, San Diego, Calif.

Application January 29, 1934, Serial No. 708,760

7 Claims. (Cl. 135—52)

This invention relates to an improved pad or cushion construction which is attachable to the upper end of a crutch to protect the arms of crutch users adjacent to the arm pits.

5. An object of the invention is to provide an improved pneumatic cushion of the character stated, thus affording a very soft and comfortable means to contact with the portion of the arms which engage the cross-piece of the crutch. Owing

10. to the fact that crutch-users are usually aged persons or else persons afflicted with feeble or impaired health, it is very important that the pads or cushions which surmount their crutches be of a particularly soft and yielding character.

15. At the same time, however, it is essential that a durable and strong character of cushion or pad be provided for the purpose stated, because of the considerable portion of the weight of the body which it is required to sustain.

20. By this invention there is provided a strong, dependable crutch cushion which may be relied upon to sustain the required weight, and yet one which will be very soft and comfortable, and which will therefore be greatly appreciated by the infirm, crippled persons who will have occasion to use the invention.

Other objects, advantages and features of invention may hereinafter appear.

Referring to the accompanying drawing, which 30 illustrates what is at present deemed to be a preferred embodiment of the invention,

Fig. 1 is a perspective view of the cushion separately shown, a portion of the outer cover thereof being broken away; Fig. 2 is a side elevation of the structure shown in Fig. 1, with the addition of a portion of the upper end of the crutch staff; Fig. 3 is a cross section on line 3—3 of Fig. 2; Fig. 4 is a sectional detail taken on line 4—4 of Fig. 2; Fig. 5 is a section similar to Fig. 4 except that a modification of the air sac is shown.

Referring in detail to the drawing, the cross-piece of the crutch consists of two cooperating concavo-convex plates 7 which serve as clamping elements gripping between them opposite overlying edge portions 8 of the air-tight sheet material of the air sac 9. Said plates may be made of hard wood, metal or other preferred materials, and are shown secured together by means of countersunk screw bolts 10. When the form of air sac shown in Fig. 4 is used a suitable adhesive coating may be applied to the contacting surfaces of the edge portions 8 to safe-guard against air leakage.

55. As indicated in Fig. 2, the cross piece of the

crutch is provided with a pair of downwardly opening sockets into which are fitted the staff pins 12 that project from the upper ends of the staff arms 13. Midway between these sockets is shown the stem 14 of an air valve, said stem being in 60 any suitable manner connected with the air chamber of the cushion in order to provide for the inflation of the air sac which forms the cushion.

The inner wall of the cushion 9 is preferably 65 made of sheet rubber, a silk outer covering 15 being desirably provided therefor to prevent the perspiration of the person using the crutches from moistening the rubber.

The side portions of the sheet rubber of the 70 air sac are made somewhat thicker than their top and bottom portions, in order that the strength may be greatest where the weight borne causes the greatest amount of flexion. This is indicated clearly in Fig. 3.

75. In Fig. 5 is shown a modification wherein the inner air sac 16 is constructed as a continuous envelope, the folded portion 17 thereof being continuous along its edge 18.

I claim:

1. The combination, with a crutch having a longitudinally split cross-piece; of a pneumatic cushion mounted upon said cross-piece, a marginal portion of said cushion being gripped between the two parts of said cross-piece. 80

2. A cross-piece consisting of two semi-circular marginal frame members bolted together, and an inflated member fastened between and filling the open space bounded by said members, said cross-piece being attachable to a staff and said inflated member being engageable with and conforming to the arm pit. 90

3. A cross-piece comprising two semi-circular marginal frame members, a semi-circular pad having its peripheral boundary secured to said members, said pad being inflatable, and an intake means whereby to inflate said pad. 95

4. A crutch part consisting of two semi-circular marginal frame members, a semi-circular inflatable cushion having an area substantially equal to the area occupied by said frame members, means to clamp said cushion between said members, and intake means whereby to inflate said cushion, said crutch part being provided with 100 sockets engageable with a staff. 105

5. A pneumatic crutch pad comprising a pair of semi-circular cross-pieces, and a semi-circular inflatable sac fastened between said cross-pieces. 110

6. A pneumatic crutch pad consisting of a

semi-circular inflatable pouch, and a pair of frame members clamped to the periphery of said pouch, said frame member having sockets for engaging a staff, and intake means whereby to 5 inflate said pad. 80

7. In a device of the kind described, in combination, a staff, a concavo-convex cross-piece mounted upon said staff, said cross-piece having its concavity directed upwardly and consisting of 10 a plurality of similarly curved elongated plates.
